BOTTLE

Robert E. Schwartz, Buffalo, N. Y., assignor to Wildroot Company, Inc., Buffalo, N. Y., a corporation of New York

Application June 13, 1955, Serial No. 36,490

Term of patent 14 years

(Cl. D58—6)

Fig. 1.

Fig. 2.

Fig. 3.

Fig. 4.

Fig. 1 is a front elevational view of a bottle showing my new design.

Fig. 2 is an end view thereof taken from the right of Fig. 1.

Fig. 3 is a vertical central sectional view thereof, taken on line 3—3, Fig. 1.

Fig. 4 is a horizontal sectional view thereof, taken on line 4—4, Fig. 1.

The rear and end views not shown are the same as the front and end views shown.

I claim:

The ornamental design for a bottle, substantially as shown and described.
